COASTER

Robert S. Pakula, New Hyde Park, N. Y., assignor
to Lapin Products, Inc., Newark, N. J., a corpo-
ration of New York

Application April 13, 1948, Serial No. 145,683

Term of patent 14 years

(Cl. D44—10)

To all whom it may concern:

Be it known that I, Robert S. Pakula, a citizen of the United States, residing in New Hyde Park, in the county of Nassau and State of New York, have invented a new, original, and ornamental Design for a Coaster, of which the following is a specification, reference being had to the accompanying drawing, forming a part hereof, in which:

Fig. 1 is a plan view of a coaster embodying my new design; and

Fig. 2 is a transverse sectional view thereof.

The dominant features of the design reside in the decorative pattern in the center of the coaster as shown.

I claim:

The ornamental design for a coaster, as shown.
ROBERT S. PAKULA.
